UNITED STATES PATENT OFFICE.

ARCH B. TAYLOR, OF CHARLOTTE, NORTH CAROLINA.

DESIGN FOR A BOTTLE.

Application filed January 7, 1929. Serial No. 29,515. Term of patent 14 years.

To all whom it may concern:

Be it known that I, ARCH B. TAYLOR, a citizen of the United States, residing at Charlotte, in the county of Mecklenburg and State of North Carolina, have invented a new, original, and ornamental Design for a Bottle, of which the following is a specification, reference being had to the accompanying drawings, forming a part thereof.

I claim:

The ornamental design for a bottle, as shown.

ARCH B. TAYLOR.
